DESIGN FOR A TOBACCO PIPE

Nathan Gold, New York, N. Y.

Application July 6, 1934, Serial No. 52,469

Term of patent 7 years

To all whom it may concern:

Be it known that I, NATHAN GOLD, a citizen of the United States, residing at New York city, county and State of New York, have invented a new, original, and ornamental Design for a Tobacco Pipe, of which the following is a specification, reference being had to the accompanying drawing, forming part thereof.

Figure 1 is a side elevation of a tobacco pipe showing my new design.

Figure 2 is a top plan view of the pipe shown in Figure 1.

Figure 3 is a bottom plan view of said pipe.

Figure 4 is a front end elevation of said pipe.

I claim:

The ornamental design for a tobacco pipe, as shown.

NATHAN GOLD.
